D11-95. OR D15,449 EX

DESIGN.

—
E. S. STRAIT.

BADGE.

No. 15,449.

Patented Oct. 7, 1884

UNITED STATES PATENT OFFICE.

E. SMITH STRAIT, OF TROY, NEW YORK.

DESIGN FOR A BADGE.

SPECIFICATION forming part of Design No. 15,449, dated October 7, 1884.

Application filed June 18, 1884. Term of patent 3½ years.

To all whom it may concern:

Be it known that I, E. SMITH STRAIT, of the city of Troy, county of Rensselaer, State of New York, have invented and produced a new and ornamental Design for Helmets, of which 5 the following is a specification.

My design relates to an ornamental helmet, as shown in the accompanying illustration, forming a part of this specification; and it consists of a helmet having a visor and cape, a visor-strap, an eagle on the front of the helmet with the wings of the eagle spread and pointed upwardly, arrows in the talons of the eagle, a plume that is at its attached end beneath the eagle, and with its free end curved therefrom upwardly and rearwardly, so as to be over the helmet.

The features of my design are shown in the annexed photograph, and designated by letter- 15 reference as follows:

The letter H indicates the helmet, V its visor, and C its cape; S, the visor-strap; E, the eagle, and P the plume. The helmet has the usual form and contour of crown N, with the visor and cape obliquely deflected from the 25 lower rim thereof.

Having thus described my design, what I claim, and desire to secure by Letters Patent, is—

The design for a helmet, consisting of the 30 rounded crown N, the visor V, cape C, the eagle E, and the plume P, as shown and described.

Signed at Troy, New York, this 16th day of June, 1884, and in the presence of two witnesses, 35 whose names were by them hereto written.

E. SMITH STRAIT.

Witnesses:

CHARLES S. BRINTNALL,
STANLEY M. HOLDEN.
